UNITED STATES PATENT OFFICE.

GUSTAVUS HAMEL, OF DE SOTO, MISSOURI.

SCHOOL DESK AND SEAT.

SPECIFICATION forming part of Letters Patent No. 400,078, dated March 26, 1889.

Application filed October 3, 1888. Serial No. 287,065. (No model.)

To all whom it may concern:

Be it known that I, GUSTAVUS HAMEL, of De Soto, in the county of Jefferson and State of Missouri, have invented a new and Improved School Desk and Seat, of which the following is a full, clear, and exact description.

The invention relates to improvements in school desks and seats, such as shown and described in Letters Patent No. 318,183, granted to me May 19, 1885.

The object of the present invention is to provide a new and improved school desk and seat, which is very simple and durable in construction, in which the seat noiselessly slides back under the desk or is easily moved into a horizontal position.

The invention consists of the standards supporting the desk, the seat-bracket pivoted to angle-irons secured to the bottom of the standards, and of braces for supporting the standards and carrying upon their upper ends pins for limiting the motion of the seat-bracket.

Reference is to be had to the accompanying drawings, forming a part of this specification, in which similar letters of reference indicate corresponding parts in all the figures.

Figure 1 is a perspective view of the improvement. Fig. 2 is an enlarged side elevation of the lower part of the improvement, and Fig. 3 is a perspective view of the upper end of the brace.

The desk A is supported by two corner legs or standards, B, which are slightly inclined, and are secured to the floor by means of angle-irons C. An inclined brace-bar, D, is secured at its upper end to each leg or standard B, at or near the middle, and its lower end is secured to the floor below the desk A. The upper end, E, of each brace D projects slightly to the front of the standard B, and carries a pin, F, extending inward and being covered by rubber or other suitable material. When the seat is in a horizontal

position, the stop-pin F is engaged by a hook, G, formed on the horizontal arm H of the seat-bracket I, having an arm, J, fulcrumed at K to the angle-iron C. A connecting-bar, L, extends from the arm H to the arm J and 50 serves as a stop when the seat is folded up. Said bar L then comes in contact with the stop-pin F. The seat-brackets I support in the usual manner the seat N, and the back O of the seat is secured to the standards or legs 55 B. When the seat is in a horizontal position, the hooks G prevent a further downward swinging motion of the seat-brackets I as the said hooks G engage the stop-pins F, as is clearly shown in Fig. 2. When the operator 60 desires to throw up the seat, he presses against the seat or seat-brackets I, so that the latter slide back into the position shown in dotted lines. This rearward swinging motion of the seat-brackets I is limited by the bars L striking against the stop-pins F. As the latter are covered with rubber or other suitable soft material, all noise is prevented in folding up or closing the seat.

Having thus fully described my invention, 70 I claim as new and desire to secure by Letters Patent—

In a combined desk and seat, the combination, with the desk-supporting standards B, of the braces D, secured to the floor at their 75 lower ends and at their upper ends to the standards B, and carrying the pins F on their inner faces, the angle-iron C, secured to the lower end of the desk-standard, and the seat-brackets I, pivotally secured at their lower 80 ends to the angle-irons, the upper arms of such seat-brackets being provided with hook G and stop-bars L, whereby the motion of the seat is limited, substantially as shown and described.

GUSTAVUS HAMEL.
